UNITED STATES PATENT OFFICE

118,302

DESIGN FOR AN ARM FOR LAMP FIXTURES

August O. Elting, Chicago, Ill.

Application October 9, 1939, Serial No. 87,590

Term of patent 14 years

To all whom it may concern:

Be it known that I, August O. Elting, a citizen of the United States, residing at Chicago, in the county of Cook and State of Illinois, have invented a new, original, and ornamental Design for an Arm for Lamp Fixtures, of which the following is a specification, reference being had to the accompanying drawing, forming a part thereof, in which:

Fig. 1 is a plan view of the arm for lamp fixtures showing my new design.

Fig. 2 is a side elevational view of the arm.
Fig. 3 is an inverted plan view of the arm.
Fig. 4 is an elevational view of one end of the arm.

I claim:

The ornamental design for an arm for lamp fixtures, as shown.

AUGUST O. ELTING.
